UNITED STATES PATENT OFFICE.

JAMES L. MACINERNEY, OF GRAND RAPIDS, MICHIGAN.

SPRING MAT FOR UPHOLSTERED ARTICLES.

Application filed February 15, 1926. Serial No. 88,236.

This invention relates to spring mats, and more particularly to structures used as interior units for various articles such as cushions, upholstered furniture, automobile seats and the like.

In devices of this character, it is desirable to use a plurality of coiled springs to cover as much as possible of the area of the article in which they are to be used; to enclose each 10 spring in fabric, not only to assist in holding the springs in place but also, by preventing the springs from interlocking in use, to eliminate noise and squeaking; to reduce the manufacturing cost as much as possible by 15 the use of a relatively cheap fabric, such as burlap; to finish the mat in a workmanlike manner so as to be easily handled as a unit, and present a neat appearance; to so construct the mat unit of parts which may be 20 readily and quickly assembled as to further reduce the cost of manufacture; and, finally, to so construct and assemble the several parts of the mat as to enable one or more parts to be easily removed for repair or replacement in the mat unit in the event of any 25 necessity therefor.

The attainment of these and other objects, and the advantages flowing therefrom, which will be manifest as I proceed with this specification, is the object of the present invention, which consists in the devices and combinations of devices illustrated, described and more particularly set forth in the appended claims.

35 In the accompanying drawings:

Figure 1 is a perspective view of a spring mat embodying my invention, partially broken away at one edge.

Figures 2 and 3 are perspective views of 40 two of the spring strips of which the mat is composed.

Figure 4 is a transverse, vertical, sectional view, showing a modified form of the strip unit illustrated in Figure 2.

45 Figure 5 is a longitudinal, sectional view through the mat, enlarged, the section being taken in the vertical plane of the dotted line 5-5 on Figure 1.

Figure 6 is a sectional view through the 50 mat, enlarged, the section being taken in the vertical plane indicated by the dotted line 6-6 of Figure 1.

Figure 7 is a perspective view, enlarged, 55 of a detail, showing the end of one of the strips, detached.

Figure 8 is a diagrammatic plan view of

the arrangement of strips forming the mat.

Figures 9 and 10 are also diagrammatic plan views showing different arrangements of strips to form a mat of the same size as 60 the mat shown in Figures 1 and 8.

Figure 11 is a perspective view of a portion of the mat arranged with a round, instead of a square, corner.

Figure 12 is a plan view of a mat, partially broken away, showing a modified 65 form.

Figure 13 is a vertical, sectional view, enlarged, of the modified form shown in Figure 12, the section being taken in the 70 plane of the dotted line 13-13 of Figure 12.

I have chosen to illustrate my invention in a mat adapted for insertion within the upholstery of a cushion seat for furniture, 75 and I have designated the same as a whole by the letter A. I have also found it convenient to illustrate the mat of a type known as 6 x 6, that is, a mat enclosing thirty-six springs; but, of course, it will be understood 80 that any other size or number of springs may be used, as desired.

Referring to Figures 1, 2, 3 and 8, it will be seen that the mat is composed of two end strips B, B, two side strips C, C, three interior strips designated as D, D, D, and a fourth interior strip designated as E. Each of the strips is made of suitable fabric, in this instance, burlap 1, and is constructed so as to embody a plurality of pockets 2, in 85 each of which is a coiled wire spring 3.

The end strips B, B, each have six pockets and six springs, but each of the side strips and the interior strips, has four pockets with a spring in each pocket. Inasmuch as the 90 side strips C, C, and the three interior strips D, D, D, are constructed alike, a description of one will suffice.

Referring, first, however, to the two end strips B, B, it will be seen that they are each 100 constructed by folding the burlap 1 so as to form a top wall 4, a bottom wall 5, and a longitudinal side wall 6. The top and bottom walls are suitably spaced apart, as hereinafter stated, to form pockets 2 within 105 which the springs 3 are placed. The three walls are joined at the two ends of the strip B by burlap pieces forming the end walls 7, 7. Intermediate the end walls and at suitable intervals, are relatively narrow partition strips 8, each partition strip being joined to the top and the bottom walls, 4,

5, by lines of stitches, and the ends 7, 7, being similarly stitched to the top and bottom walls 4, 5, as well as to the side wall 6. This arrangement is more clearly seen in the detail view shown in Figure 7. The springs 3 in this instance are three inches in diameter and six inches long, and when inserted in the pockets 2, are compressed or snubbed so as to be under tension, and the pockets 2 are substantially rectangular in outline and of a size to hold said three inch springs, as clearly shown in Figures 5 to 7, inclusive.

It will be observed that such a strip of spring-enclosing pockets is closed by fabric 15 at its two ends, on one side, and on its top and bottom, but is open at one side.

In practice, I prefer to make the top and bottom walls of fabric slightly wider than the three inch width of the pocket and to fold over, toward each other, the excess of material indicated at 9 and 10.

The side strips C, C, and the interior strips D, D, D, are similarly constructed, with the exception that the end walls 7, 7, of the strip B, are not present in the said side and interior strips, but in lieu thereof I use a partition strip 11, similar to the partitions 8, and secured in the same manner. Thus, in addition to these strips being open 30 at one side, the springs are also partially exposed at each end.

The strip E is made of burlap, with the top, bottom and side walls, 4, 5, 6, respectively, with the partitions 8, and with partitions 11 at each end, but with the springs exposed only partially at each end of the strip. It will be seen by reference to Figure 2, that the top wall 4 and the bottom wall 5 are not provided with the narrow excess material 9 and 10, as in the case of the other strips, but are provided with portions 12, 13, respectively, which are joined together at 14 by a line of stitches 15, to form a side wall, thus completely enclosing the springs 3, by top, bottom and two side walls.

In assembling these strips B, B, C, C, D, D, D, and E, thus described, to form the mat A, I arrange them in the form shown by diagrammatic Figure 8. The side walls 6 of the end strips B, B and the side strips C, C, are of course on the outside of the mat, leaving the open side of each of these strips facing inwardly. The side wall of one of the strips D is positioned adjacent the open 55 side of the end strip B, and all of the strips D, D, D, face in the same direction. The end of each strip D, D, D, is adjacent to the inwardly open side of the side strips C, C, the partition strip 11 in each instance spacing the two adjacent springs from each other. The strip E is then positioned between the open side of the other end strip B and the open side of the adjacent interior strip D. The two closed sides of the strip 65 E thus spaced the springs in strips B and D

from each other and the end strips 11 of the strip E space its springs from the adjacent springs in the side strips C, C.

When thus positioned, the various strips are cross tied by strings S, in a manner familiar to the upholstery art, both over the tops 4 of the several strips and the bottoms 5. This cross tying of the strips by strings S, S, is sufficient to firmly unite the strips into a unitary structure A, easy to handle and transport.

It will be noted that there is no real necessity for the use of the material 9, 10 on the top and bottom of the strips, excepting that it makes a neater finish by bending over these portions 9, 10, in a direction toward each other. It will also be observed that it is not necessary to construct the fourth side of the strip E in the particular manner shown in Figure 2, that is to say, having the two portions 12 and 13 united centrally of the side; and I have therefore shown, in Figure 4, as one modification, among others, the top wall 4 extended over to form a side wall 16, the lower edge of which will overlie the upturned portion 10 of the bottom wall 5, and may or may not be secured thereto by stitching, as preferred.

From the foregoing, it will be understood that a very considerable amount of fabric will be saved by making all of the strips, save one, with an open side; substantially an entire yard of fabric being thus saved in a mat of the size referred to, and a saving in the cost of manufacture is thereby effected. It will also be understood that by making the strips with an open side, the springs may be positioned in their respective pockets very readily, by unskilled labor and without the aid of special tools or machinery.

In the diagrammatic illustration of Figure 8, it will be observed that the strips D, E and B run in parallel relation, but this is not necessary, as various arrangements of strips may be made. For example, in Figure 10, the strips C, D and E are in parallel relation, and in Figure 9, the arrangement is such that all of the strips are of the same length, that is to say, six pockets having six springs, and all the strips are parallel. In this arrangement the strips will all be made like the strips B, B, and all but one will have a top, a bottom, a side wall and two end walls, and have one open side. One strip will be provided with two side walls, similar to the strip E.

Various other arrangements will occur to those skilled in the art; the essential point being that a plurality of strips be used, all but one of which will be provided with an open side.

Where it is desirable to use the mat A in a structure having a rounded instead of a square corner, the end spring of one of the strips will be omitted, and the fabric of the

side wall 6 of adjacent strips will be brought together and tied or sewed, as desired. A portion of the space formed by the omission of the end pocket of one of the strips, will be 5 filled by the upholsterer with stuffing material in the usual manner. Such a construction is illustrated in Figure 11.

It will be observed that in the arrangement shown in Figures 1 and 3, where the 10 strips are provided with narrow pieces of fabric 9 and 10 on the open side of the strip, said narrow pieces are tucked in and lie parallel against the wall 6 of the next or adjacent strip. In some instances, I prefer 15 not to do this, and arrange the mat as shown in the modification, Figures 12 and 13, where the top strip 9 is substantially in extension of the top 4 and overlies the top 4 of the next adjacent strip, and the same is true of 20 the bottom extension 10. This is more clearly brought out in the enlarged view, Figure 13.

In this arrangement, the edge of the end wall 7 of the end strip B, instead of being 25 secured by stitching or tying to the fabric of the end strip C, as shown at 17 in Figure 1, overlies said fabric as shown at 18 in Figure 12.

Various other modifications in detail will 30 occur to those skilled in the art, all of which I desire to be included in the scope of my invention, so long as the mat as a whole is composed of a plurality of strips of fabric formed into a series of pockets enclosing a 35 spring in each pocket, all of the strips, save one, having the springs exposed to view along one side.

I claim as my invention:

1. The method of assembling a plurality 40 of spring containing strips to form a mat unit, some of said strips having a continuous top, bottom and one side wall, and one open side, and one strip having a continuous top, bottom and two side walls, and end walls for 45 some of said strips, which consists in grouping the several strips with the open side of one strip against the closed side of some strips and against the closed ends of other strips, whereby the various springs are surrounded only by one thickness of burlap.

2. The method of making a cellular structure containing springs in a plurality of 50 pockets, which consists in making a fabric strip folded longitudinally into substantially 55 rectangular form and interiorly spaced apart by fabric strips to form a plurality of pockets, with a spring in each pocket, and a plurality of fabric strips in which the fabric is folded longitudinally to form the 60 top, bottom and one side only, and which is interiorly provided with spaced apart strips to form pockets, each pocket contain-

ing a spring, and assembling the closed unit and the plurality of open units with the initially open side of one strip against the 65 closed side of the adjacent strip, whereby the various springs are surrounded only by one thickness of fabric, and securing the various strips so positioned, together, to form the completed unit. 70

3. In a mat construction, a plurality of 75 spring containing fabric strips in which the fabric is folded longitudinally to form continuous top, one side and bottom walls for a plurality of pockets, partition strips connected to the top and bottom walls, a spring in each pocket, the initially open longitudinal side of one spring strip being arranged to lie against the fabric side of an adjacent strip, a spring containing strip comprising 80 the top, bottom and two side walls of a plurality of pockets arranged to lie against and close the initially open side of one of said first-mentioned strips, and walls closing 85 the ends of some of the strips, the free longitudinal margins of the top and bottom walls of one strip being connected to an adjacent strip.

4. In a mat construction, a plurality of 90 spring containing fabric strips in which the fabric is folded longitudinally to form continuous top, one side and bottom walls for a plurality of pockets, partition strips connected to the top and bottom walls, a spring in each pocket, the initially open longitudinal side of one spring strip being arranged to lie against the fabric side of an adjacent strip, a spring containing strip comprising 95 the top, bottom and two side walls of a plurality of pockets arranged to lie against and close the initially open side of one of said first-mentioned strips, walls closing the ends 100 of some of the strips, the free longitudinal margins of the top and bottom walls being inturned to extend at right angles to said top and bottom walls, and means for connecting adjacent spring strips. 105

5. A mat composed of a plurality of fabric strips, the fabric being folded longitudinally to form a continuous top, one side and a 110 bottom wall for a plurality of pockets, partition strips connected to the top and bottom walls, end walls for said strips, a spring in each pocket, the springs in the pockets of one strip being separated from the springs 115 in the pockets of an adjoining strip by the longitudinal side wall of said adjoining strip and the end walls of some of the strips abutting the initially open side of adjacent pockets. 120

In testimony that I claim the foregoing as my invention I affix my signature this 5th day of February, 1926.

JAMES L. MACINERNEY.
